UNITED STATES PATENT OFFICE.

CHARLES E. CREECY AND ALEXANDER B. BURNS, OF WASHINGTON, D. C.

FIRE-ESCAPE.

SPECIFICATION forming part of Letters Patent No. 279,348, dated June 12, 1883.

Application filed December 29, 1882. (No model.)

To all whom it may concern:

Be it known that we, CHARLES EATON CREECY and ALEXANDER B. BURNS, of Washington, in the District of Columbia, have invented certain new and useful Improvements in Fire-Escapes; and we do hereby declare that the following is a full, clear, and exact description of the invention, which will enable others skilled in the art to which it appertains to make and use the same, reference being had to the accompanying drawings, which form a part of this specification, and in which—

Figure 1 is a horizontal sectional view of our improved combined fire-escape and stand-pipe. Fig. 2 is a side elevation of a portion of the same. Fig. 3 is a horizontal sectional view, showing a modified construction of the clamping-collar; and Fig. 4 is a detail view of the complete ladder and stand-pipe with its appurtenances.

Like letters of reference indicate corresponding parts in all the figures.

Our invention has relation to that class of fire-escapes which consist of a ladder fixed permanently to the outside wall of a building in proximity to the windows, reaching from the ground to the roof of the building, and provided with suitably-arranged balconies or platforms for enabling the inmates of a house, in case of a fire, to reach and escape by the ladder through the windows.

Our improvement consists in so arranging the stand-pipe and ladder that they will mutually support or brace each other by means of a peculiarly-constructed clamping-collar made in one or more pieces, which permits the firemen and other persons in ascending or descending the ladder to take hold of or grasp the side rails of the same, which cannot well be done where the stand-pipe itself constitutes one of the sides or side rails of the ladder, owing to its dimensions.

In the accompanying drawings, A denotes the stand-pipe, which may or may not be provided with a duplex inlet or so-called "Siamese attachment," A', at the bottom. At each story it is provided with the usual hose-coupling to permit a stream of water to be turned into any one of the several stories, as well as at the outlet or top, for the purpose of flooding the roof when desired by attaching a hose and noz-

zle. The stand-pipe is suitably fixed in the platforms or balconies outside the several stories, by means of which access is afforded to the ladder from the inside, the ladder being in like manner suitably fixed in the platforms or balconies with which it communicates. These platforms or balconies may be constructed and arranged in any approved manner, and, inasmuch as they form no part of our present invention, are not shown on the drawings.

B B are the side rails, and C the rounds, of the ladder. The ladder and stand-pipe are buckled together in close proximity by means of clamping-collars D, made in one or more pieces, as shown in Figs. 1 and 3, respectively, and having squared bails or loops D', shaped to fit the side rails, B. These clamping-collars may be placed under the ladder-rounds or above them, or alternately under and above them, as desired. A block, F, of wood, iron, or other suitable material, is placed within the loop D' between the side rail, B, and the stand-pipe, that side of it facing the stand-pipe being concaved to fit the swell or bulge of the pipe, as shown in Fig. 1. There is, however, no necessity of placing one of these blocks in each of the clamping-collars. In practice it will answer the purpose to place them suitable distances apart to properly space the ladder and stand-pipe; or they may be dispensed with altogether by so constructing the clamping-collars that a space will be left between the side rail of the ladder and the stand-pipe. The object of this is to leave a space between the ladder and the pipe, which will enable persons ascending or descending the ladder to grasp the rails on both sides, and thus prevent accidents from slipping or making false steps on the rounds—accidents which are liable to occur during the excitement of a fire.

By tightening up the bolt or bolts E, which are inserted through the lips d d, by means of their nuts e, the collars will be clamped tightly around the stand-pipe, so as to cause their loops D' to hug the ladder-rail tightly, as shown in the drawings. In this manner the stand-pipe and ladder will mutually support one another, permitting both to be constructed of lighter material than otherwise without in the least affecting their efficiency. In other words, the proximity of the stand-pipe to the ladder,

connected, as they are, by the clamping-collars D, constitutes one solid and substantial structure, without actually making the stand-pipe a part of the ladder, or vice versa.

5 Having thus described our invention, we claim and desire to secure by Letters Patent of the United States—

1. The stand-pipe A and ladder composed of the rounds C and side rails, B B, connected 10 to mutually support or brace one another by clamping-collars D, provided with spacing-blocks F, substantially as and for the purpose shown and set forth.

2. The clamping-collars D, having squared 15 loops D', and adapted to be clamped around the stand-pipe A and side rail, B, by nutted

bolts E e, substantially as and for the purpose shown and set forth.

3. The combination, in a fire-escape, of the stand-pipe A, clamping-collars D D', nutted 20 bolts E e, spacing-blocks F, and ladder composed of the rounds C and side rails, B B, substantially as and for the purpose herein shown and set forth.

In testimony that we claim the foregoing as 25 our own we have hereunto affixed our signatures in presence of two witnesses.

CHARLES EATON CREECY.
ALEXANDER B. BURNS.
